UNITED STATES PATENT OFFICE.

BELDEN D. GILLIAM, OF CHICAGO, ILLINOIS.

BUTTON-APPLYING IMPLEMENT.

Application filed July 15, 1926. Serial No. 122,867.

This invention relates to devices for applying buttons or pronged disks to articles and particularly to applying more or less ornamental buttons, as they may be termed, 5 to shoes or other leather or rubber articles.

The general object of the present invention is to provide a device of this character by which pronged disks of celluloid may be applied to shoes, boots, galoshes, etc., said 10 device embodying opposed jaws, one of them carrying an anvil and the other a plunger so constructed that the plunger will support the button and when the jaws are brought together the prongs of the button will be 15 caused to pass through the material, bent inward against the anvil, and eventually be clinched.

Other objects will appear in the course of the following description.

20 My invention is illustrated in the accompanying drawings wherein:—

Figure 1 is a side elevation of my improved implement;

Figure 2 is a section on the line 2—2 of 25 Figure 1;

Figure 3 is a side elevation showing the implement closed;

Figure 4 is a sectional view at right angles to the section shown in Figure 2 and 30 showing a button being applied;

Figure 5 is an underside face view of the plunger;

Figure 6 is a top plan of the anvil;

Figure 7 is a sectional view of the button.

35 Referring to these drawings it will be seen that the implement consists of the jaws 10 and 11, each jaw being provided with a handle 12 crossing the handle of the other jaw and pivoted thereto by the pivot 13. The 40 jaw 10 is bifurcated at 14 in a plane at right angles to the plane of movement of the jaw and passing vertically through the jaw for movement therein is the shank 15 of a button holder. This button holder and shank 45 consists of a rod circular in cross section and fitting loosely in an aperture 16 extending through a collar 17. This collar fits in the bifurcation 14. This collar is formed with projecting pins 18 and extending transversely through the collar is a pin 19.

The upper end of the shank 15 carries outwardly projecting pins 20 engaging the pins 18 and the pins 20 are the coiled contractile springs 21 which, when in place, act to urge 55 the rod or shank 15 downward through the collar. The shank 15 is formed intermediate

its ends with a longitudinally extending slot 22 and the pin 19 extends through this slot 22 and thus the plunger 15 has a limited movement within the collar. The lower end 60 of the plunger is formed with undercut oppositely disposed lugs 23 for the purpose of engaging the button and holding the button while the prongs are being forced through the leather of the article and clinched. 65

Mounted upon the jaw 11 is an anvil 24, the face confronting the plunger 15 being formed with two small recesses 25, each recess being beveled downward and toward the center of the anvil. The button which is 70 designed to be applied by this implement consists of a head or top 26 of celluloid or like material, this celluloid head or top being attached to a metallic base 27 and the metallic base is provided with the prongs 28 which initially are in a somewhat convergent relation. The head of this button projects out beyond the prongs and, therefore, this head may be engaged between the lugs 23 and thus the button supported on the plunger. 75

In the operation of this device the button is placed on the plunger, the article to which the button is to be applied is disposed between the button and the anvil. The jaws are then closed by the handles 12 and as the 80 jaws are closed, the springs 21 will first cause the prongs of the button to pass through the goods and be forced against the anvil and then as the jaws are further compressed, the anvil will cause the prongs of 85 the button to be forced inward and clinched on the under side of the article. It is essential in this device that the plunger shall have a limited movement through the collar in order to permit the springs 21 to resiliently force the prongs through the leather, 90 rubber, or other material to which the button is being applied. 95

The button is designed to be used on galoshes, slippers, pumps, and the like either 100 as an ornamental feature or for the purpose of carrying a monogram whereby the articles may be readily identified. Obviously, however, I do not wish to be limited to this use of this button applying device. 105

I claim:—

1. A button applying implement of the character described comprising opposed jaws having crossed, pivoted handles, one of said jaws being formed with an anvil and the opposite jaw being bifurcated at right angles to the plane of movement of the jaw, 110

- a collar disposed in said bifurcation, a plunger slidingly mounted in the collar, the plunger having a longitudinally extending slot, a pin passing through the collar and through said slot, and coiled contractile springs operatively engaged with the collar and with the outer end of the plunger and urging the plunger inward to the extent permitted by said slot, the inner end of the plunger being so formed as to support the button to be applied.
2. A button applying implement of the character described comprising opposed jaws having crossed, pivoted handles, one of said jaws being formed with an anvil and the opposite jaw being bifurcated at right angles to the plane of movement of the jaw, a collar disposed in said bifurcation, a plunger slidingly mounted in the collar, the plunger having a longitudinally extending slot, a pin passing through the collar and through said slot, and coiled contractile springs operatively engaged with the collar and with the outer end of the plunger and urging the plunger inward to the extent permitted by said slot, the inner end of the plunger being formed with opposed undercut lugs adapted to engage the head of the button to be applied, the anvil being formed with beveled recesses to engage, bend, and clinch the prongs of the button.
3. A button applying implement of the character described comprising opposed jaws having handles, the handles being crossed and pivoted to each other, one of said jaws being provided with an anvil, the other jaw being bifurcated at right angles to its plane of movement, a collar mounted within said bifurcation and having laterally projecting pins, a plunger sliding through the jaw and said collar and having a longitudinally extending slot, a pin extending through the collar and through the slot whereby the plunger may have limited longitudinal movement, pins projecting laterally from the outer end of the plunger, and coiled contractile springs engaged with the pins on the collar and with the pins on the plunger, that end of the plunger adjacent the anvil being formed to provide two opposed undercut lugs adapted to engage and support the head of a button, and the anvil having recesses beveled inward toward the center of the anvil and adapted to engage and clinch the prongs of the button.

In testimony whereof I hereunto affix my signature.

BELDEN D. GILLIAM.
